CLOTHES WRINGER

Edgar D. Misner, Detroit, Mich., assignor to
 Lovell Manufacturing Company, Erie, Pa., a
 corporation of Pennsylvania

Application February 9, 1934, Serial No. 710,394

11 Claims. (Cl. 68—32)

This invention relates to clothes wringers or pressure exerting devices of the type most commonly used by housewives to extract the water from clothing or the like, after the same has 5 been through the process of washing.

Clothes wringers of the type most widely used at the present time are of heavy wood and iron construction, and when completely assembled are, as a general rule, too heavy for the average 10 housewife to handle without bodily discomfort resulting from such effort.

It is customary to provide the usual clothes wringer with manually operable screws for adjusting the distance between the wringer rolls, 15 which screws not only require the exertion of considerable strength to operate, but the proper adjustment of which is difficult for a person not having quite some mechanical experience or aptitude.

20 The principal object of the present invention is to provide a clothes wringer of marked simplicity and compactness of construction of neat and attractive appearance and of even more importance, so much lighter in weight than the 25 common heavy wood wringers as to be capable of being handled by the housewife without undue physical exertion.

A further object is to provide a light weight 30 wringer of great strength and durability and in which the wringer rolls automatically adjust 35 themselves thereby enabling the usual adjusting screws to be eliminated.

Another object of the present invention is to 40 provide a wringer of new and improved construction in which the pressure of the wringer rolls is effected by the employment of spring 45 steel shafts of relatively small cross sectional area to which are vulcanized outer coverings of soft rubber, the wringer rolls being assembled in the wringer frame with the spring steel shafts under an initial tension sufficient to provide an effective wringing pressure.

A further object of this invention is to provide 50 a new and improved wringer frame or housing formed of two identical sheet metal stampings which, when bolted together, provide not only a gear housing, but a container for the rollers and roller shaft bearings.

Another object of my invention is to provide 55 new and improved drip aprons, so constructed as to feed material passing through the wringer rolls towards the center of the wringer.

A further object of my invention is to provide 60 new and improved gearing to compensate for variations in differences between gear centers

and angular changes in the gears due to the flexure of the spring steel wringer roll shafts.

Another object of this invention is to provide new and improved swiveled clamping brackets 5 to enable the wringer to be readily attached to either straight sided tubs or tubs with curved sides.

The above and other objects of the present invention will appear more fully from the following more detailed description and by reference 10 to the accompanying drawing forming a part hereof and wherein:

Fig. 1 is a front elevation, partly in section, 15 of a wringer constructed in accordance with the principles of the present invention;

Fig. 2 is a vertical section taken substantially on the line 2—2 of Fig. 1;

Fig. 3 is a vertical section taken substantially 20 on the line 3—3 of Fig. 1;

Fig. 4 is a top plan view of one of the drip 25 aprons;

Fig. 5 is a front elevation of the wringer illustrating the manner in which the spring steel 30 shafts flex to permit relatively thick articles to pass between the rolls;

Fig. 6 is a horizontal section taken substantially 35 on line 6—6 of Fig. 5;

Fig. 7 is an enlarged view showing the manner 40 in which the gears adjust themselves.

As shown in the drawing the wringer frame is 45 preferably formed of similar sheet metal dished stampings 10, 10', having top, bottom and side flanges, the edges of which contact in abutting relationship when said stampings are assembled to form a smooth exterior housing in which all 50 of the parts are encased; the members 10, 10' each having a central rectangular opening 10^b to expose the bight of the wringer rolls.

Suitable shaft bearings 11, preferably formed 55 of oil impregnated wooden blocks, are housed 40 within the wringer frame, and held rigidly therein by means of the frame bolts 12 which pass through suitable apertures in the frame members 10, 10' and said bearing blocks and are threaded on one end to receive the nuts 13. 45 When the nuts 13 are tightened on the bolts 12, the two frame members 10, 10' are clamped together in assembled condition and as the bolts 12 pass through the bearing blocks 11, the tightening of the nuts 13 also tends to hold these 50 bearing blocks rigidly in place.

The wringer rolls 14, 14' are composed of soft 55 rubber, vulcanized upon tempered spring steel shafts 15, 15', of such small diameter as to permit the shafts to flex and permit relatively thick

articles to pass between the rolls. The spacing of the bearing holes 16, 16', in the bearing blocks 11 for the shafts 15, 15', is such that when the rolls and shafts are assembled in the frame, the 5 shafts are placed under an initial tension such as to insure the proper roll pressure.

The use of small spring steel shafts as cores for the rubber rolls which are assembled under an initial tension has marked advantages because it not only enables the proper roll pressure to be secured for thin goods, but as the shafts are sufficiently flexible to yield when thicker pieces of material are passed between the rolls; the spring action of the shafts insures an automatic increase of roll pressure directly proportional to the thickness of the material and eliminates the necessity for the use of adjusting screws. It therefore becomes possible, by the simple expedient of employing the small spring 10 steel shafts and a correct spacing of the bearing holes 16, 16' in the bearing blocks 11 to construct the wringer so that substantially uniform pressure will always be maintained between the rolls from one side to the other thereof, and there is no 15 possibility for the housewife to disturb the proper alignment of the rolls as with the usual type wringer provided with adjusting screws.

As the rolls are assembled under an initial tension it also becomes possible to simplify the driving gearing as the drive may be effected simply by the frictional engagement between the rubber surfaces of the rolls. In order to lighten the physical effort required to rotate the rolls a gear reduction is provided between the driving gear or pinion 17 which is, as clearly shown in Fig. 2, 20 much smaller than the gear 18 with which it meshes and which is non-rotatably secured to the shaft 15 of the upper roll 14. Due to the fact that when thicker materials are run through the wringer the spring steel shafts will flex considerably at their central portions, the ends of the shafts 15, 15' will in effect pivot slightly in their bearings and thereby cause the gears 17, 18 to move into closer meshing engagement.

For the purpose of compensating for this flexural movement of the shafts, the gear 18 is constructed of a plurality of similar gear sections, 25 preferably made of sheet metal stampings, which are non-rotatably mounted on the end of shaft 15 but which are sufficiently loose on the shaft and are free of each other so as to permit the teeth of each gear section to align automatically in the most effective driving relationship with the teeth of the pinion gear 17.

In order to hold the gear sections 18 on the shaft 15 and also to prevent the outer gear section from rubbing against the inner walls of the frame members 10, 10', a washer 19 is loosely mounted on the boss 20 of pinion gear 17 and so that it overlaps at its periphery the edge of the outer gear section 18.

Formed integrally with the driving pinion 17 is a sleeve like extension 20* which extends through the aperture 16' in the journal block 11 and 30 forms a bearing for said pinion; the roller 15' of the lower roll 14' being rotatably received in said extension 20*, so that the latter serves not only as a journal shaft for the pinion but also as a bearing for one end of the roller shaft 15'.

As it is one of the principal objects of the invention to provide a small compact wringer structure capable of being stored in a small space when not in use while at the same time capable of heavy duty use, the crank handle 21 of the 35 wringer is made detachable. This is accom-

plished by providing the boss 20 of the pinion gear 17 with a pair of bayonet slots 20b with which is adapted to engage a pin 22 which extends diametrically across the inner end of the handle and the ends of which project sufficiently to lie flush with the outer surface of the boss 20 when the crank handle is engaged therewith.

A pair of drip aprons 23, 23' preferably formed of sheet metal stampings are each provided at each end with a small tab or ear 24 10 adapted to be received within a punched out recess 24' in the sheet metal frame members, each frame member 10, 10' being provided with a pair of such recesses, one at each side of the rectangular opening 10b thereof. The apron 23 15 on the feed-in side of the wringer is provided with a marked concavity, as indicated by the reference character 23b, extending towards the center of the wringer, and said apron also extends downwardly and outwardly to terminate 20 in a concaved edge 23c, this double concavity of the apron serving to place a drag on the material being fed through the rolls and tending to make such material track towards the center of the wringer as will be readily understood; 25 this construction of the apron on the feed-in side being particularly effective, in combination with the flexible spring steel shafts of the rollers and the resulting camber of the rolls that occurs when material is fed between the rolls, 30 to cause the material, even if inserted between the rolls adjacent the sides of the wringer, to move automatically towards the center thereof. The aprons are preferably provided with side wings 25 which fit neatly against the side edges 35 of the rectangular openings of the frame members and the bottom of each apron rests on the bottom edge of said opening which, as will be understood, is shaped to conform to the concavity of the apron. When the aprons are assembled in the frame members they are firmly held in position by the clamping action of the frame bolts 12 on the frame members which cause the tabs 24, to be clamped tightly between the sides of the bearing blocks 11 and 40 within the depressions or recesses 24'.

A pair of clamping brackets 26, are provided to attach the wringer to a laundry tub, wash tub, or the like, and each consists of an inverted U-shaped member having an L-shaped clamp, 50 the upper portion 28 of which is reduced to pass slidably through an aperture provided in one leg of the U-member in which is also provided a screw threaded aperture to receive a screw 29 having wing head 30. The inner end of the 55 wing screw 29-30 is reduced as at 32 to pass rotatably through a hole in the clamp 27 and is headed over to secure said screw to the clamp. Pads 33 of any suitable resilient material are secured to the clamp 27 and to the opposed leg 60 of the U bracket to prevent marring the surface of the tub and to insure a better gripping effect.

In order that the wringer may be attached with equal facility to a curved wash tub as to a straight laundry tub, the brackets 26 are 65 swivelly secured to the wringer housing by means of rods 34 which pass rotatably through the openings 35 in the heads of the lower frame bolts 12, the lower ends of said rods being reduced and riveted to the brackets 26. The upper ends of 70 the rods 34 are screw threaded as at 37 to engage within threaded apertures in the heads of the upper frame bolt 12.

The construction and arrangement of the brackets 26 not only provides a swiveled con- 75

nection of such brackets that permits them to be placed at any required angular position for attachment to tubs of different size and shape, but also permits the brackets to be detached entirely from the wringer frame for compactness in storing or shipping.

The manner in which the parts are assembled will be readily understood, the bearing blocks and gears being placed on the ends of the wringer roll shafts, the aprons 23, 23' are placed within their respective frame members with the tabs 24 seated within the corresponding recesses 24' in the wringer frame. The two frames are then placed with the edges of their inwardly turned flange portions in abutting relationship and the frame bolts 12 are passed through the holes in the frame members and the bearing blocks after which the nuts 13 are screwed upon the threaded ends of the bolts and are tightened up, thus causing all of the parts of the wringer to be securely clamped together.

The wringer is operated in the usual well known manner, the end of the crank handle 21 being inserted into the bore of the boss 20 of the pinion gear 17 with the pin 22 of the crank handle in engagement with the bayonet slots provided in said boss. The reduction provided between the gears 17 and 18 makes it possible to rotate the wringer rolls when relatively heavy goods are passed between them with but a small amount of manual effort on the part of the user. As the pinion gear 17 is not directly connected to the shaft of the lower roll, the drive is effected from the pinion 17 to the gear 18 to the upper roll which drives the lower roll by the frictional engagement between the peripheries of the rubber coatings of the rolls. Due to the fact that the spring steel shafts of the rolls are placed under an initial tension when the rolls are assembled in the frames, sufficiently tight frictional engagement between the rubber coatings of the rollers is present to insure that the lower roll will be driven by the rotation of the upper roll. There being no adjusting screws, substantially uniform pressure across the entire width of the rolls will always be preserved. When relatively heavy materials are fed between the rolls, the flexibility of the spring steel shafts will permit such shafts and the rubber coatings thereon, to spread apart to permit the passage of such heavy materials. For the purpose of preventing any binding of the ends of the spring steel shafts in the bearing blocks, the upper bearing 16 of each block is made elongated to compensate for the flexing of the shafts when the material is fed through the rolls. Other advantages of the construction, such as the functioning of the aprons 23 and the cambering of the rolls and shafts thereof to cause goods passing through the wringer rolls to automatically track towards the center, and the arrangement and construction of the gear 18 to compensate for flexing of the roller shafts, have been heretofore discussed.

The construction of the wringer frame of sheet steel stampings, with the edges of the stampings arranged and tightly clamped in close abutting relationship, results in obtaining a structure of particularly neat and attractive appearance. The stampings may be enameled and decorated in attractive colors and a smooth surface obtained that can be very quickly and readily cleaned. All of the working parts are completely enclosed within their outer casing.

While I have described a satisfactory construc-

tional example embodying the principles of my invention, it will be understood that many changes, variations and modifications may be resorted to without departing from such principles.

I claim:

1. In a wringer, a frame, a pair of wringer rolls, each having a central tempered cylindrical spring steel shaft and a yielding coating secured thereto, said rolls being assembled with said shafts into the frame under an initial tension, the cross sectional area of said shafts being restricted so as to impart sufficient flexibility to said shafts to permit the wringer rolls to spread and thereby allow heavy materials to pass therebetween, the inherent elasticity of said shafts and the initial tensioning thereof providing a roll pressure automatically proportioned in accordance with the thickness of the material passed between said rolls.

2. In a wringer, a pair of wringer rolls, a frame comprising a pair of similar sheet metal members each having a peripheral flange, the edges of said flanges being adapted to engage in aligned abutting relationship when assembled to form a smooth exterior housing, said housing at each end having a bearing compartment, bearing blocks in each of said compartments having a pair of fixed bearings for the reception of the ends of the wringer roll shafts and means for securing said frame members and bearing blocks in assembled condition comprising frame bolts which pass through said bearing blocks and frame members.

3. In a wringer, a pair of wringer rolls, a frame comprising a pair of frame members having a line of separation vertically and lengthwise of the frame, and each having a centrally located opening therein to expose the bight of said rolls, means for clamping said frame members in assembled condition to form a housing in which said wringer rolls are received, a pair of bearing blocks completely enclosed within said housing and means for clamping said frame members and bearing blocks in fixed assembled position comprising the clamping bolts extending from front to rear of the wringer, a pair of drip aprons, each being provided with a pair of laterally projecting portions adapted to extend through said openings into the interior of said housing and to be clamped between said frame members and bearing blocks to hold said drip aprons securely in position.

4. In a wringer, a pair of wringer rolls each having a tempered flexible cylindrical spring steel shaft with a yielding coating secured thereto, a frame comprising a pair of sheet metal sections, which, when assembled, form a housing having bearing compartments at each end thereof, a bearing block mounted in each bearing compartment and having a pair of fixed bearings for the ends of the wringer shafts, the spacing between the pairs of each block being such as to place an initial tension upon said spring steel shafts when said rolls are assembled in said blocks and frame whereby said shafts will normally extend in slightly cambered relationship, and a feeding apron secured in said frame having a concaved upper face and a concaved forward edge, the camber of said rolls and the concavities of said feeding apron co-operating to cause materials fed through said rolls to track towards the center of the wringer.

5. In a wringer, a pair of wringer rolls, each having a centrally tempered flexible spring steel

- shaft with a yielding coating secured thereto, bearings for the end of said shaft so spaced that when said rolls are assembled in said bearings said shafts will be placed under an initial tension with said shafts in reverse cambered relationship, a gear for driving said rolls including a driving pinion and a driven gear, said driven gear consisting of a plurality of thin gear members unsecured to each other but non-rotatably secured to one of said roll shafts whereby relative movement between said gear members may occur to compensate for flexure of said spring steel shafts.
6. In a wringer, a pair of wringer rolls, each comprising a central flexible tempered spring steel shaft, each of said shafts having a yielding coating secured thereto, means for placing said shafts under an initial tension when they are assembled in said wringer with the coatings thereof in tight frictional engagement, thereby to provide a wringing pressure, a driving pinion having a sleeve-like portion to provide a bearing for one end of one of said shafts, a driven gear in meshing engagement with said pinion and non-rotatably secured to the other of said shafts, and means for rotating said pinion and gear to drive said other shaft, the rotation of said wringer rolls being effected by the frictional engagement between the coatings of said rolls.
7. A wringer, as set forth in claim 6, in which said pinion is provided with a hollow boss having a pair of bayonet slots therein and a handle adapted to be detachably received within said boss, said handle being provided with means for engagement with said bayonet slots.
8. A wringer, as set forth in claim 6, in which said driving gear consists of a plurality of gear laminations non-rotatably secured to one of the wringer shafts but unsecured to each other.
9. In a wringer, a pair of wringer rolls, a sectional metal frame, bearings for said wringer rolls and headed bolts for clamping said frame sections and bearings in assembled condition, and means for clamping said wringer to a tub comprising a pair of clamping brackets rotatably but detachably secured to the heads of said frame bolts whereby said brackets may be adjusted to different angular positions relative to said wringer for permitting the same to be attached to tubs of different contour and for permitting said clamping brackets to be entirely disengaged from the wringer for convenience in shipping and storing.
10. In a wringer, a pair of wringer rolls, a plurality of metal frame sections, bearings for said wringer rolls and bolts for clamping said frame and bearings in assembled condition, said bolts being provided with enlarged portions projecting outwardly beyond the frame, said portions being provided with vertically aligned apertures and means for securing said wringer to a supporting structure comprising rods rotatably secured in said aligned openings and clamping devices secured to the lower ends of said rods.
11. In a wringer, a frame, a pair of wringer rolls mounted therein, means for detachably securing said wringer to a supporting structure comprising two pairs of extensions projecting from one side face of said frame, the members of each pair of extensions being located in vertical alignment and being provided with vertically aligned apertures, one of said apertures being threaded, a vertically extending rod having a portion thereof threaded for engagement with the threaded aperture, rotatably received in each pair of extensions and clamping devices secured to the lower end of said rod.

EDGAR D. MISNER.
